(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the delineated portion 8 in FIG. 1;

FIG. 9 is an enlarged view of the delineated portion 9 in FIG. 1; and,

(Continued)

FIG. 10 is an enlarged view of the delineated portion 10 in FIG. 3.

The dashed broken lines in the figures illustrate portions of the electronic device that form no part of the claimed design. The dot-dot-dash broken lines in the figures delineating portions of the claimed design that are illustrated in enlargements form no part of the claimed design.

1 Claim, 7 Drawing Sheets

Related U.S. Application Data

a continuation of application No. 29/863,683, filed on Dec. 21, 2022, now Pat. No. Des. 1,007,454, which is a continuation of application No. 29/762,008, filed on Dec. 14, 2020, now Pat. No. Des. 975,074.
